Joseph D. Warren, James B. Scofield, Isaac Hardwell
and Augustus T. Jones, of Stamford, Conn.

Whole No. 1369. Letters Patent No. 4. Dated Feb. 5, 1861.

The schedule referred to in these Letters Patent and making part of the same.

To all whom it may concern:

Be it known that we, Joseph D. Warren, James B. Scofield, Isaac Hardwell and Augustus T. Jones, of Stamford, in the State of Connecticut, have invented and produced a new and original design, being an ornament to be placed on stoves: of which the following in connection with the drawing hereto annexed is a full description.

The design is in the form and configuration of an ornament impressed upon the cover and base of a stove in a cylindrical form, suitable for halls, and apartments.

This configuration is formed by a series of small uniform raised figures, somewhat in the shape of a wedge, side by side, around the circumference of the cover, and base, with several rows of beads as shown in the drawing, and around the door. A modification in the same style is placed on the urn. For a more particular description reference is made to the far simile drawing annexed, making a part of this specification.

That we claim as our invention and distinctly secured by Letters Patent, is the form, configuration and arrangement of the raised figures and beads as above described.

Stamford Connecticut, February 3, 1860.

Witnesses.

End. Charles N. Olmsted.
